UNITED STATES PATENT OFFICE.

ELBERT G. HOWARD, OF DENVER, COLORADO, ASSIGNOR OF ONE-FOURTH TO JOSEPH B. NICHOLIC AND ONE-TENTH TO E. M. LELLESS, BOTH OF DENVER, COLORADO.

TOY TRACKWAY.

Application filed June 7, 1924. Serial No. 718,616.

This invention relates to certain improvements in toy trackways and it is an object of the invention to provide a novel and improved device of this general character provided with a trackway which is adapted to be traversed by a spinning top.

It is also an object of the invention to provide a novel and improved device of this general character comprising a trackway disposed on a predetermined incline and which is adapted to be traversed by a spinning top together with a platform or table arranged at the entrance end of the trackway and upon which the spinning top is adapted to be initially positioned.

Another object of the invention is to provide a novel and improved device of this general character comprising an inclined trackway disposed in a desired course and which is provided at its lower or exit end with a table or platform to receive the top after the same has passed along the trackway, said top being retained by said table or platform until it finishes its spin.

The invention consists in the details of construction and in the combination and arrangement of the several parts of my improved toy trackway whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation illustrating a toy trackway constructed in accordance with an embodiment of my invention;

Figure 2 is a horizontal sectional view taken through the device as disclosed in

Figure 1;

Figure 3 is a view in perspective of the upper platform or table as herein disclosed, and the adjacent end portion of the trackway;

Figure 4 is a view in elevation illustrating a further embodiment of my invention.

As disclosed in the accompanying drawings, B denotes a base member herein disclosed as somewhat conoidal in form and more particularly in simulation of a moun-

tain. This member B as herein disclosed is hollow with its wall formed of papier mâché or any other suitable material.

The wall of the base member B is provided with diametrically opposed openings 1 positioned at a predetermined point intermediate the ends of the member B and arranged within said member and bridging the space between the lower margins of the openings 1 is a track 2 maintained in applied or working position by the supporting and bracing members 3. The top or apex portion of the member B is flattened, said flattened surface constituting a table or platform 4 disposed on the desired incline, the sides of said table or platform converging toward the lower end of the table or platform, said converging sides and the upper wide end of the table or platform 4 are defined by the upstanding flanges 5.

Leading from the lower or restricted end of the platform 4 is a track 6 disposed on a predetermined incline and extending spirally around the upper portion of the base B and leading to one of the openings 1, said track 6 being continued by the track 2 disposed through the base B. Leading from the opposite end of the track 2 or the second opening 1 is a track 7 extending on a predetermined incline spirally around the lower portion of the base B, said inclination, however, as herein disclosed, being reversed to the inclination of the upper track 6. The lower or exit end of the track 7 is continued by a bottom table or platform 8 having its margins defined by the upstanding flanges 9.

The tracks 2, 6 and 7 as herein disclosed are each U-shaped in cross section with its base or intermediate portion a relatively narrow and with the side members or flanges b thereof comparatively low or short with respect to said intermediate or base portion a.

In practice, a top T of any desired type is caused to spin upon the upper or top table or platform 4 and owing to the inclination of said table or platform the top will be caused to enter upon the upper end portion of the track 6 and to traverse said track down to the track 2 and thence along said track 2 through the body B in an imitation of passing through a tunnel, it being understood that the track 2 is disposed on sufficient inclination to assure the requisite

movement of the top T therealong. As the top passes out of the body B it continues its travel down and along the track 7 and upon the lower or bottom table or platform 8 where it is adapted to spin out.

In the embodiment of my invention as illustrated in Figure 4, I provide a central tower C on the top of which is suitably mounted a table or platform 4' constructed and arranged in somewhat the same fashion as the table or platform 4 hereinbefore referred to. The lower or exit end of the table or platform 4' is continued by a track 10 disposed on a downward incline and spirally around the tower C, the lower end of said track 10 delivering upon the bottom table or shell 8^a substantially the same as the table or lower shell 8 hereinbefore referred to. The track 10 at predetermined points therealong is supported and braced by the members 11 suitably secured to said track 10 and to the tower C. The track 10 is also U-shaped in cross section and substantially the same type as the tracks 2, 6 and 7 hereinbefore referred to.

From the foregoing description it is thought to be obvious that a toy trackway constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A toy trackway adapted for use in connection with a spinning top comprising

two platforms, means for supporting said platforms one above the other, the upper platform being arranged on an incline, and a track leading from the low point of the upper platform to the second platform, said track being U-shaped in cross section, the marginal portions of the upper platform being provided with upstanding flanges opposed flanges converging toward the track.

2. A toy trackway adapted for use in connection with a spinning top comprising two platforms, means for supporting said platforms one above the other, the upper platform being arranged on an incline, and a track leading from the low point of the upper platform to the second platform, said track being U-shaped in cross section, the track between the platforms being disposed in an indirect path and on a downward incline, both of said platforms having their marginal portions provided with upstanding flanges, opposed flanges of the upper platform converging toward the track.

3. A toy trackway adapted for use in connection with a spinning top comprising, in combination, a substantially conoidal supporting member having its top surface flattened to constitute a platform and being disposed on an incline, marginal portions of the platform being defined by upstanding flanges and the lower portion of the platform being restricted, a track leading from the lower or restricted end of the platform and disposed spirally around the supporting member on a predetermined incline, the lower end of the track being continued by a platform, the marginal portions of said lower platform being defined by upstanding flanges.

In testimony whereof I hereunto affix my signature.

ELBERT G. HOWARD.
